UNITED STATES PATENT OFFICE.

WILLIAM H. COLLIER, OF JACKSON, TENNESSEE.

COMBINED TYPE-WRITING AND PRINTING MACHINE.

No. 901,682.

Specification of Letters Patent.

Patented Oct. 20, 1908.

Application filed January 2, 1908. Serial No. 409,026.

To all whom it may concern:

Be it known that I, WILLIAM H. COLLIER, a citizen of the United States, residing at Jackson, in the county of Madison and State 5 of Tennessee, have invented certain new and useful Improvements in a Combined Type-Writing and Printing Machine; and I do hereby declare the following to be a full, clear, and exact description of the same, 10 such as will enable those skilled in the art to which it appertains to make and use the same.

My invention relates to combined type-writing and printing machines and involves 15 improvements on and modifications of the machine of that character illustrated and described in my Patent No. 858,857, dated July 2, 1907.

Machines of this class are particularly 20 adapted for the printing of circulars, letters, etc., which are in the main the same but which differ in minor respects, as for example, in the address.

The machine herein described is substantially 25 an ordinary typewriter to which has been applied a printing bed adapted to coact with the platen of the typewriter to print from paper carried by said platen. In the machine herein described this printing bed is mounted to slide in the same carriage upon which the said platen is mounted, said bed sliding in a direction at right angles to that of the movement of said carriage. This construction obviates any necessity 30 of adjusting the carriage to any particular point with reference to the striking point of the typewriter type, before operating the printing bed. The same inking ribbon is used for making impressions from 35 the typewriter type and from the type on the printing bed, one end of this ribbon being preferably upon a reel mounted on the carriage, and the other end upon a reel 40 mounted on the carrier of the said printing bed, means being provided whereby the ribbon is fed automatically.

The objects of my invention are to improve the construction of the combined type-writing and printing machines such as referred to; to insure that the impression 45 made by the printing surface of the said printing bed shall be made at the desired

point on the paper on the typewriter platen, and this without the necessity of setting the typewriter carriage at any particular point; 55 to improve the ink-ribbon carrying and feeding means of such machines; and generally to make the machine simple, compact and reliable and in general structure similar to an ordinary typewriter. 60

I will now proceed to describe my invention with reference to the accompanying drawings, in which one form of combined typewriter and printing machine embodying my invention is illustrated, and will 65 then point out the novel features in claims.

In said drawings: Figure 1 shows a top view of my said combined typewriting and printing machine; Fig. 2 a side view thereof; Fig. 3 a detail top view of the printing-bed carrier; Fig. 4 shows a detail section through the ribbon carrying reels and platen; Fig. 5 shows a detail section from front to rear through the platen carriage and printing bed, the platen being shown 75 elevated; and Fig. 6 shows a similar view, the platen being shown lowered into operative position.

I have shown my invention applied to a typewriting machine of the general character of that shown in my said Patent No. 858,857, namely the machine known on the market as the "Smith Premier" machine, certain modifications having been made in the said machine to adapt it for carrying a 80 printing bed. Since the said machine is well known, and since also my invention is equally applicable to most of the other commercially known typewriters, I have not illustrated in full the mechanism of such 85 machine, and particularly have not shown many of the parts and sub-mechanisms of such machine which are in no wise affected by the application of my invention to the machine. 90

It will be understood that I do not limit myself to the use of my invention on any particular make of typewriter.

In the drawings 1 indicates the frame of the machine, 2 the key board thereof and 3 100 the usual wires connecting the keys of said key board to the type bars (not shown) of the machine.

4 designates the platen carriage, mounted

to slide laterally of the machine on ways 5, and 6 designates the usual typewriter platen. For simplicity of illustration I have not shown, in connection with this platen, the 5 usual paper holding and paper feeding devices, but it will be understood that the platen and platen carriage are provided with such devices.

7 is the said printing-bed carrier and 8 the 10 printing surface thereof. I have not illustrated any particular type surface as comprised in said printing surface, but customarily the surface will be one comprising type-faces, such for example as the surface 15 produced by assembled types or a stereotype plate. The printing-bed carrier 7 is mounted to slide from front to back in the platen carriage 4 itself, the printing surface 8 on said carrier being at such height that when 20 said carrier is moved forward as described, said surface will press the inking ribbon 9 (Figs. 4, 5 and 6) against paper on said 25 platen and so will print an impression on such paper. When said carrier is in its extreme rearward position its front part is in front of the platen and therefore there is in said carrier an opening 10 in front of the printing surface 8 through which the type bars of the typewriter may strike the ribbon, 30 against the paper on the platen 6, the same as in an ordinary typewriter.

One end of the ribbon 9 is upon a reel 11 mounted to rotate upon the platen carriage and provided with a return spring 12 tending 35 normally to wind the ribbon up on said reel. The other end of the ribbon is upon a reel 13 mounted in bearings at the front end of the printing-bed carrier 7. It will be seen that as this carrier 7 is moved forward, the said ribbon 9 will move with it, passing the paper on platen 6 at the peripheral speed of said paper and (what is the same thing) at the speed of movement of the printing surface 8, and so causing no blurring on the paper; and it will also be seen that upon the backward movement of the said printing-bed carrier the ribbon will return and will be wound up again on said reel 11. To feed the ribbon forward slowly from 40 reel 11 to reel 13, I provide feeding mechanism comprising a worm wheel 14 on said reel 13, a worm 15 mounted in bearings on said carrier 7 and engaging said worm wheel, a ratchet wheel 16 on said worm, and 45 a ratchet pawl 17 arranged to engage a tooth of said ratchet wheel 16 during each backward movement of said carrier 7 and near the end of such backward movement, so rotating said reel 13 intermittently and there- 50 by winding the ribbon slowly from the one reel to the other.

In some cases it is desirable to be able to make an insertion at some point in the body

of the matter to be printed by the printing 65 surface 8. In such case an opening similar to opening 10 may be left in the carrier 7 and printing surface, where such insertion is to be made. In Fig. 1 I have indicated such an opening at 18.

What I claim is:—

1. In a combined typewriter and printer the combination of a typewriter platen, a carriage therefor, a frame, typewriter printing mechanism, and a printing bed movable with said platen carriage and movable with 75 respect to said carriage in a direction transverse to the axis of rotation of said platen.

2. In a combined typewriter and printer the combination of a typewriter platen, a carriage therefor, a frame, typewriter printing mechanism, and a printing bed movably mounted in said platen carriage to move in 80 a direction transverse to the axis of rotation of said platen.

3. In a combined typewriter and printer the combination of a platen, a carriage therefor, a frame, typewriter printing mechanism, a printing bed movable with said carriage and movable in a direction transverse to the axis of rotation of said platen, 85 ribbon carrying means mounted on said carriage and other ribbon carrying means 90 mounted on said printing bed.

4. In a combined typewriter and printer the combination of a platen, a carriage therefor, a frame, typewriter printing mechanism, a printing bed movable with said carriage and movable in a direction transverse to the axis of rotation of said platen, a ribbon carrying reel mounted on said platen carriage, another ribbon carrying reel mounted on said printing bed, one of said reels 95 provided with automatic return means, and feeding means engaging the other of said 100 wheels.

5. In a combined typewriter and printer the combination of a platen, a carriage therefor, a frame typewriter printing mechanism, a printing bed movable with said carriage and movable in a direction transverse to the axis of rotation of said platen, 110 a ribbon carrying reel mounted on said platen carriage and provided with automatic return means, another ribbon carrying reel mounted on said printing bed and 115 ratchet mechanism for feeding the ribbon comprising a ratchet wheel mounted on said printing bed and a pawl adapted to engage said reel.

6. In a combined typewriter and printer, 120 the combination with the rotary and axially movable platen and printing mechanism of a typewriter, of printing means comprising a support for a printing surface in co-operative relation with respect to said platen, said support adapted to be moved past said 125

platen and in a direction transverse to the axis of rotation of said platen, and also to be moved with the platen, and having an opening within the area of its printing portion through which the printing mechanism of the machine may act upon a surface carried by said platen.

In testimony whereof I affix my signature, in the presence of two witnesses.

WILLIAM H. COLLIER.
